FOLDING TABLE.

1,416,815.

Specification of Letters Patent. Patented May 23, 1922.

Application filed November 15, 1920. Serial No. 424,055.

To all whom it may concern:

Be it known that I, WALTER S. GRAFFAM, a citizen of the United States, residing at Shrewsbury, in the county of Worcester and State of Massachusetts, have invented a new and useful Folding Table, of which the following is a specification.

This invention relates to a table of the type which can be folded up into small compass 10 for convenience in transportation.

The principal objects of the invention are to provide a table having a top made up of a plurality of sections or panels so related to each other that they can be rolled up to 15 form a small hollow rectangular case; to connect with these plates the supporting legs in such a way that they can be folded up in a very small compass together with all the braces and located inside said rectangular 20 case; to provide these parts in such form that when collapsed and folded up the whole structure will be of such dimensions as to be stored easily in an automobile or the like or a trunk and carried about from place to 25 place; to provide a construction which, in spite of the above mentioned qualities, can be unfolded and set up rapidly in the form of a table by any person without experience or mechanical ability and without the use of 30 tools or special detachable parts; to provide a construction in which the table can be set at varying heights from the ground and also can be set at different angles so that if placed on sloping ground the table top can 35 be brought to a horizontal position, thus rendering the table particularly suitable for use in lunching, camping out and the like; and to provide a device of this character which can be made of comparatively light 40 material, as wood or sheet metal, that will be strong and rigid when set up. The table is compact, universal, not seriously affected by heat or moisture, easily cleaned, sanitary, will hold all the food that would usually 45 be piled on it, will stand rigidly on uneven or sloping ground and can be made practically indestructible when formed entirely of metal. The invention involves various features of construction including the pro- 50 gressively increasing width of the panels of which the table top is made, to permit of rolling up into a rectangular box form, a particular way of pivotally connecting the cross bars to the panels of the table top, 55 means for holding the ends of the cross bars, means for reinforcing the sheet metal edges

of the table top, a special form of locking device on the end of the braces provided with a friction washer, a novel construction of the legs by which a very simple and inexpensive 60 foot is provided and other features as will appear.

Reference is to be had to the accompanying drawings in which—

Fig. 1 is a perspective view illustrating 65 this invention in the form of a complete table shown set up in its normal position, part of it being broken away and appearing in section to show interior construction;

Fig. 2 is an end view showing in full lines 70 an arrangement of the same elements by which the table can be set up with the top nearer the ground and showing in dotted lines how the same elements can be adjusted to permit of setting it up on sloping ground 75 in such a way as to keep the top horizontal;

Fig. 3 is a perspective view of the entire table folded up in small compass;

Fig. 4 is a perspective view showing a form of spring clip for holding the end of the 80 cross bar;

Fig. 5 is a perspective view showing a reinforcement of the edge of the table top;

Fig. 6 is a perspective view of a leg and brace;

Fig. 7 is a plan of one of said braces;

Fig. 8 is an edge view;

Fig. 9 is an end view thereof;

Fig. 10 is an edge view of one of the cross bars;

85

Fig. 11 is an end view of the same;

Fig. 12 is an elevation of the blank of which one of the legs is formed, showing it before the foot portion is formed completely, and

95

Fig. 13 is a bottom plan view of one of the legs in its complete form.

In the form of the invention shown in the drawings, I have illustrated it as applied to a table which is provided with a top formed 100 of sheet metal, preferably galvanized iron. This top is shown as made up of a series of plates or panels arranged in two series. Every alternate plate constitutes a panel A of nearly the same width, but each one 105 slightly wider than the alternate one to the left. The intermediate plates are of varying widths gradually increasing from the narrowest one A¹ next to the edge panel to the widest one A² next to the other edge panel. 110 Each of these plates is provided with integral tongues bent over at the edge to form a

hinge construction. These hinges are made by turning integral portions of each plate or panel downward and inwardly to form a cylinder a . On each edge of each plate a plurality of these cylinders are provided of equal length and equally spaced apart. As each plate or panel is provided with these hinge sections on each edge, those on each one registering in the spaces of the adjacent one, it will be obvious that a single hinge pin can be inserted through from one end to the other of each joint thus formed when the parts are assembled. This constitutes a series of parallel hinges pivoting each panel to the next one on both sides.

The two end panels are bent down at their outer edges to form sides a^2 and these are bent up inwardly on the inside to strengthen these walls. For the purpose of further reinforcement I provide a steel bar 10 on the inner side of each of the vertical walls a^2 and in contact with the upwardly turned inner edge. This bar 10 projects beyond the inner wall at both ends. Its end is then turned inwardly over the end of the upturned inner wall a^2 at both ends. This securely clamps the re-inforcing bar 10 in position with its outer and inner surfaces intimately engaging the inner surfaces of the two parts of the wall a^2 . In this way the longitudinal edges of the table top are materially strengthened and made comparatively rigid though light.

Permanently connected with the end panel A on one side are two cross bars 11, swinging on vertical pivots 13. Consequently they swing in a plane parallel to the table top when expanded. I have shown a thick connecting piece 12 securely riveted to the end of one cross bar and connected with the table top by a pivot 13 in the form of a rivet. The object of this is to be able to swing these cross bars inwardly under the first panel without danger of breaking and one of them in contact substantially with the inner wall of the vertical edge a^2 . For this purpose one pivot 13 is much nearer the wall a^2 than the other one.

When about to be used they are swung outwardly in the opposite direction and their free offset ends 14 are forced under the slanting end of a spring clip 15 riveted to the opposite end panel A of the table. This spring clip has a recess 9 formed by bending, into which this end of the cross bar is inserted and which holds it against twisting or dislodgment. This construction is substantially duplicated at the two ends of the table.

It is to be noted that each of these cross bars, being in the form of an angle iron, has a horizontal top under the top of the table for strengthening it and receiving the weight of the sheet metal panels. The bottoms of the hinges a which project below the

panels normally rest on these two horizontal surfaces.

The outer vertical wall of each cross bar is provided with perforations 16. Each of these perforations is shown as having a circular central opening and two opposite horizontal slots extending from it. If the table is to be used only for the purpose indicated in Fig. 1, in which it is about the height of any ordinary table, only one pair of these perforations will be used in each cross bar, but for the purpose of adjustment, additional perforations are shown. These perforations are to receive turn buttons 17 located on braces 18. Each of these turn buttons comprises a shank passing through a perforation in the brace and headed over at 19 on the other side. A spring washer 20 is placed under the head of the button to hold it frictionally in any position in which it is placed. The braces 18 are each pivoted on one of the flanges of a leg 21. Each of these legs is in the form of an angle iron and they are all pivoted at the top by means of horizontal pivots 22 to the vertical walls of the cross bars 11. It will be seen therefore that these legs all swing on what are parallel axes considering the table as in the position shown in Fig. 1. It will be seen also that several braces 18 are pivoted on what can be considered the inner surfaces of one wall of each leg so that when folded they fold inside these legs and take up practically no room.

These legs are arranged in two pairs obviously, the pair connected with the same cross bar swinging toward each other. The angle irons of which these three members consist have a certain relationship. One leg is mounted so that it folds within the angle iron forming the cross bar to which it is pivoted and the other folds on its outer surface. Therefore, when these three members are folded together they have the thickness vertically of one of them and the thickness transversely of two of them. This constitutes an economy in the spacing of these elements when folded.

Each leg also is provided with an improved form of foot for the purpose of simplifying and cheapening the construction and yet having full strength. In cutting out these legs originally they are cut at the bottom to form two opposite triangular projections 23 as shown in Fig. 12. In completing these legs these two angular ends are bent inwardly at right angles along horizontal lines. Then the legs are bent longitudinally and centrally at right angles. That brings these angular edges into contact with each other as shown in Fig. 13. This gives a flat bottom or foot to the leg having a continuous lower surface.

I also provide two pairs of side braces or struts 25. These are shown as pivoted

on horizontal axes to the outer surfaces of the legs 21 at a slight elevation above the bottom thereof. These legs are provided with perforations like the perforations 16 located at the proper height to receive turn buttons 17 like those described above on the end of the opposite legs. Only one set of these perforations is required. These braces as stated are located on the outside and cross each other to connect the legs in pairs. When folded up they lie parallel with the outer flange of the leg and merely add their thickness to the room occupied thereby.

Starting with table all folded up as shown in Fig. 3 it is set up in the following manner: First it is unrolled so that the several panels lie flat on the ground bottom side up. The operator stands on the side of the table top to which the cross bars are pivoted so that they are close at hand. Then the left hand end of the cross bar 11 which is pivoted at his right, together with the connected group of legs and braces, is lifted about two inches and is held up in that position. Then the right hand end of the leg of this group is lifted and dropped back toward the operator over the flange a^2 . Now the other cross bar 11 with its attached braces and legs, is swung inwardly on its pivot 13 about half way leaving it resting on the inner side of the table top diagonally. Then the first group of parts is swung all the way around to a position at right angles with that which it occupies when folded, and its end is snapped back of the spring clip 15. That cross bar therefore is fixed in position and the two legs carried by it are in position for unfolding. Now the other cross bar is similarly snapped into position.

This leaves both cross bars in their final place ready for the legs to be swung out. In doing this, the long brace 25 on either side is swung inward while the leg is being raised on its pivot 22. The short brace is dropped down on the inside of the leg and is locked in place by inserting the button 17 into the proper slot in the cross bar 11. The button is then turned crosswise in the slot to hold it there. All four legs are erected in the same way so that they stand vertically. The only thing remaining to do now is to lock the long braces in place and stand the table right side up.

If a low table is desired so that the campers can sit around it on the ground, the operation is substantially the same in unfolding except that the legs are crossed as indicated in Fig. 2 and the braces 18 are also crossed. I have shown two sets of perforations 16, the inner set being used if the table is desired to be located at an intermediate height not fully shown in the drawings.

If the table is to be used on a side hill, the only difference is that one pair of braces 18 is inserted in the outer pair of perforations 16 while the other pair are inserted in the inner pair of perforations. The braces 25 are fixed in the same way in all cases.

In folding the table the opposite operation is obviously necessary. It is first turned bottom side up. The braces 25 and 18 are disconnected at their free ends and swung parallel with their respective legs, occupying very little room as indicated. The legs are swung down against the cross bars and the cross bars with their connected legs and braces are swung inwardly on their respective pivots 13 in an order opposite to that described above. This brings the two groups of pivoted members inside of the first panel A, one of the groups resting up against the inner side of the flange a^2 and the other coming close to it but all within the area of this panel. This panel then is rolled over so that the next panel A' which is narrower, will assume a vertical position. One more turn and the next panel A which is nearly the same width as the first one is brought into parallel position therewith underneath it but spaced therefrom. This operation is continued until all the panels are folded over. This leaves a box-like casting as indicated in Fig. 3. Two of the legs only appear in that figure because the others are hidden by the right hand wall as they do not extend as far in the left hand direction.

It is to be noted that each panel is made wide enough to overlap the one inside it and project far enough beyond its edges to permit of this folding operation. For this purpose they are made of the progressively increasing width from one edge of the table to the other. The only thing that is necessary in order to hold the construction together is to confine the outer panel by placing a strap around the whole structure if desired. This folded structure is of the same length as the table top and of a width equal to that of the widest panel. Its thickness is the same as the width of the widest panel of the narrow series of panels and that is only a little greater than twice the width or thickness of one of the legs. It will be seen, therefore, that the whole structure can be folded into an extremely small compass and that it is convenient to carry and easily set up as well as being so constructed as to be capable of satisfying the varying conditions required in using it for lunches, etc. by the way-side.

Although I have illustrated and described only a single embodiment of the invention, I am aware of the fact that many modifications can be made therein by any person

skilled in the art without departing from the scope of the invention as expressed in the claims.

Therefore, I do not wish to be limited to 5 all of the details of construction herein shown and described but what I do claim is:—

1. A folding table having a top comprising two series of parallel hinged panels 10 els, one series progressively increasing in width all the way from one side to the other, the panel of that series near one edge being the narrowest and the one near the other edge being the widest of that series.

15 2. A folding table top consisting of two series of panels arranged alternately and hinged together along their sides and those of each series progressively increasing in width from one side to the other to permit 20 some to be folded within the areas occupied by others, but those of the other series all being of nearly the same width.

3. A folding table top consisting of sheet metal panels, each having integral cylindrical projections by which they are hinged together, certain of said panels being of 25 sufficient width to receive between their cylindrical projections the total width of the fourth panel therefrom on one side.

30 4. In a device as described, in combination, a table top consisting of a series of panels hingedly connected together, the side panel being formed with vertical flanges thereupon doubled inwardly at the bottom, a pair 35 of cross bars having their opposite ends frictionally received by said side panel to retain the several panels in still relationship, and a spring clip carried by one of said panels adapted to bind against said cross bars to 40 further hold them against said panels.

45 5. In a device as described, in combination, a table top consisting of a plurality of panels, cross-bars contacting said panels, means for loosely connecting said panels together edgewise, the side panel being formed with double edge flanges, a stiffening bar within each of said double flanges bent over at its ends to hold it in position, and spring 50 clips adapted to removably contact said cross bars with said panels.

55 6. In a device as described, in combination, a table top, crossbars pivoted to said table top, a pair of parallel vertical legs pivotally connected to each of said cross bars at opposite sides of said table top, and brace arms pivoted to said legs on axes transverse to the first named pivotal connections for holding said legs apart.

60 7. In a device as described, in combination, a table top, cross bars made of angle iron mounted therebelow transversely thereof, a series of legs also of angle iron, one side of each cross bar having holes therethrough, brace arms pivotally carried by 65 said legs and formed with upper terminals

adapted to project into said holes, said terminals being pivoted to admit the insertion of said terminals into said holes, and means for spreading said leg portions apart in collapsible relation.

70

8. In a device as described, in combination, a table top, angle iron cross bars having sides contacting flat against said table top and sides perpendicular thereto, angle iron legs, brace arms carried by one side of each 75 leg inside the angle iron and engaging the perpendicular sides of said cross bars, and another set of brace bars pivotally carried by said legs on their outer sides and engaging these same sides of other legs to space 80 said legs apart.

9. In a device as described, in combination, a table top, cross bars pivotally carried by said table top, a series of legs pivoted to the cross bars, means for locking said table 85 top upon the upper ends of said legs, a series of brace arms carried by said legs foldably, and means for retaining said brace arms against said leg portions.

10. In a device as described, in combination, a table top, a series of legs arranged therebeneath, said legs being angle irons throughout their lengths, brace arms carried by said legs and engaging said table top, and another set of brace arms carried by and 95 engaging the lower portions of said legs to hold them apart.

11. In a device as described, in combination, a table top, a series of legs arranged therebeneath, a set of brace arms pivotally 100 connected to said legs at their lower ends, said brace arms being adapted to diagonally project alongside said legs and find lodgement in other legs, and means for movably locking said table top upon the upper ends 105 of said legs.

12. In a folding table, the combination with a top comprising a plurality of pivotally connected panels of varying width, a pair of cross bars permanently pivoted to 110 one side edge panel, legs permanently pivoted to each cross bar, and braces pivoted to the legs, the two groups of cross bars, legs, and braces being foldable into a rectangular space formed between the narrow- 115 est four panels near one edge of the top when each is swung into a position perpendicular to the next one.

13. In a folding table, the combination with a top comprising a plurality of pivotally connected panels of varying width, a pair of cross bars permanently pivoted to 120 one side edge panel, legs permanently pivoted to each cross bar, and braces pivoted to the legs, the two groups of cross bars, legs, 125 and braces being foldable into a rectangular form by swinging them back against the panel to which the two cross bars are pivoted and rolling the top over and over in the same direction.

130

14. In a folding table, the combination of a top, with legs permanently pivoted thereto and adapted to support the top at a maximum height when held perpendicular to the top, means for holding them in such perpendicular position comprising braces pivoted to the legs, and means for holding said legs in crossed inclined relationship to support the top at a lower elevation comprising provisions below the top for holding the free ends of the braces at a different point.
15. In a folding table, the combination of a top, with legs permanently pivoted thereto and adapted to support the top at a maximum height when held perpendicular to the top, means for holding said legs in crossed inclined relationship to support the
- top at a lower elevation, and means to hold one pair of them at a different angle from the other pair to support the top horizontally when the bottoms of the legs rest on an inclined surface.
16. In a folding table, the combination of a top, with legs permanently pivoted thereto and adapted to support the top at a maximum height when held perpendicular to the top, and means for holding said legs in crossed inclined relationship to support the top at a lower elevation, and at different angles, to provide a plurality of heights for the table top.

In testimony whereof I have hereunto affixed my signature.

WALTER S. GRAFFAM.
